(57) **CLAIM**

The ornamental design for a power head for counter-top oven, as shown and described.

DESCRIPTION

FIG. 1 is a perspective view of a power head for a counter-top oven showing my new design, which is assembled to the oven base and heating chamber shown in broken lines;

FIG. 2 is a top view of the power head of FIG. 1.

FIG. 3 is a left side view of the power head of FIG. 1, and the right side view is a mirror image thereof.

FIG. 4 is a front view of the power head of FIG. 1; and, FIG. 5 is a rear view of the power head of FIG. 1.

The details shown in broken lines are for illustrative purposes only and form no part of the claimed design.
